[57] CLAIM

The ornamental design of a combined fishing bucket
and fishing rod holder, substantially as shown.

DESCRIPTION

FIG. 1 is a perspective view of a combined fishing
bucket and fishing rod holder showing my new design;
FIG. 2 is a front elevational view thereof;
FIG. 3 is a typical side elevational view thereof;
FIG. 4 is a top plan view thereof; and
FIG. 5 is a bottom plan view thereof.
